Primary Examiner—Brian N. Vinson
Attorney, Agent, or Firm—Feix & Feix[57] **CLAIM**

The ornamental design for the beverage can dispenser, as shown and described.

DESCRIPTION

FIG. 1 is a left side isometric perspective view of the beverage can dispenser of the present invention, the right side isometric perspective view being a mirror image thereof;

FIG. 2 is a top plan view of FIG. 1;

FIG. 3 is a left side elevation view of FIG. 1, the right side elevation view being a mirror image thereof;

FIG. 4 is a front end view of FIG. 1;

FIG. 5 is a rear end view of FIG. 1; and,

FIG. 6 is a bottom plan view of FIG. 1.

The broken lines showing the connector screws along the left and right side walls of the beverage can dispenser are for illustrative purposes only and form no part of the claimed design.
